BLOCK SIGNALLING SYSTEM FOR RAILROADS

Thomas J. Judge, Rochester, N. Y., assignor to General Railway Signal Company, Rochester, N. Y.

Application March 14, 1952, Serial No. 276,647

4 Claims. (Cl. 246—33)

This invention relates to signalling systems for railroads, and it more particularly pertains to systems of the absolute permissive block type for single track railroads.

In signalling systems of the absolute permissive block (APB) type, directional stick relays are employed for the respective intermediate signals in a block between passing sidings to provide signal control for following train movements. At a double intermediate location, one of such stick relays is required for each signal, and it is generally picked up upon the entrance of a train into the track section governed by the associated signal. This of course requires a track relay at the intermediate signal location for each track section adjoining that location. The provision of track relays in this manner requires additional track circuits because it is necessary to add cut sections whereby there will always be a track relay at each double intermediate signal location for each of the signals.

According to the present invention, the installation of cut sections to provide the above allocation of track relays is not required as both stick relays at a double intermediate signal location are governed by the same track relay. Thus it is necessary to have but one track relay at a double intermediate location as compared to the usual requirement of two relays. This is because the stick circuits are so organized that the stick relay for one direction of traffic is picked up upon acceptance of the associated signal, while the stick relay for the other direction of traffic is picked up when a train enters the track section in approach to the associated signal. In this way control in each case is by the same track circuit, and thus the track circuit chosen for the control of the stick relays is the circuit having a track relay at the intermediate signal location, the other track circuit adjoining the signal location being permitted to have its track fed at the signal location.

An object of the present invention is therefore to reduce to a minimum the number of track circuits required in an APB signalling system by controlling the stick relays at a double intermediate signal location by the same track relay.

Other objects, purposes, and characteristic features of the present invention will be in part obvious from the accompanying drawings, and in part pointed out as the description of the invention progresses.

In describing the invention in detail reference is made to the accompanying drawing in which similar letter reference characters are used to designate parts having similar features and functions, with preceding numerals being employed to indicate particular locations or devices with which the respective parts are associated.

For the purpose of simplifying the illustration and explanation, the various parts and circuits constituting the embodiment of the invention have been shown diagrammatically and certain conventional illustrations have been employed, the drawing having been made more with the purpose in mind of making it easy to understand the prin-

2

ciples and mode of operation, than with the idea of illustrating the specific construction and arrangement of parts that would be employed in practice. Thus, the relays and contacts are illustrated in a conventional manner and symbols are used to indicate the connections to the terminals of batteries, or other sources of electric current, instead of showing all of the wiring connections to these terminals. The symbols (+) and (—) are employed to indicate the positive and negative terminals respectively of suitable batteries, or other sources of direct current. In the drawings, equipment is located at several different points along the trackway, and it is assumed that suitable sources of direct current, as represented by the symbols, are provided at each of these different spaced points as required.

The trackway illustrated is assumed to be a portion of trackway constituting a block extending between two passing sidings of a single track railroad, the block being divided into respective track sections including the track sections 2T and 4T which are illustrated as adjoining an intermediate signal location wherein signal 4 is provided for governing eastbound traffic and signal 5 is provided for governing westbound traffic. It is assumed that similar double intermediate signal locations are provided at the opposite ends of the track sections 2T and 4T, and thus the signal 2 is provided for governing eastbound traffic into the track section 2T and signal 6 is provided for governing eastbound traffic leaving the track section 4T. Similarly the signal 3 is provided for governing westbound traffic leaving track section 2T and signal 7 is provided for governing westbound traffic entering track section 4T.

Although the signals employed can be of any conventional type, for this embodiment of the present invention, the signals are considered to be of the searchlight type such as is disclosed, for example, in the patent of O. S. Field, No. 2,239,316, dated April 22, 1941.

Each signal has associated therewith a yellow-green repeater relay YGP which has slow drop away characteristics as is the usual practice for repeater relays of this type. These relays are normally energized because of their associated signals being normally clear.

Line circuits are shown for the control of the signals, these line circuits being of the three-wire type, although it is to be understood that line circuits of the two-wire type may be employed in accordance with the requirements of practice.

Directional stick relays 3S, 4S, 5S, and 6S are illustrated as being associated with the respective signals 3, 4, 5, and 6.

Having thus described the system apparatus, more detailed consideration will hereinafter be given as to the specific organizations when considering various typical conditions of operation of the system.

Operation

The conditions of the apparatus illustrated correspond to the conditions of the system when there is no train present in the block. Thus the respective signal mechanisms are energized with a polarity to cause actuation of the signals to clear positions, the signals being dark in accordance with the provision of approach lighting. Thus the signal 2 is energized over the line circuit from the next signal in advance by a circuit extending from (+), including front contact 20 of relay 4YGP, line wire 21, front contact 22 of relay 2TR, back contact 23 of relay 3S, winding of signal 2, common wire 24, and front contact 25 of relay 4YGP, to (—). Signal 4 similarly has its mechanism energized with a positive polarity by a circuit including front contact 26 of relay 6YGP, line wire 27, front contact 28 of relay 4TR, back contact 29 of relay

55, winding of signal 4; common line wire 30, and front contact 31 of relay 6YGP.

In accordance with signal 4 being energized with a positive polarity, the contacts of the signal mechanism are actuated to their right-hand positions; and thus the relay 4YGP is energized by an obvious circuit including contact 32 of the mechanism of signal 4 in its right-hand position.

For westbound traffic, the mechanism of signal 7 is energized with a positive polarity through front contact 33 of relay 5YGP, common wire 30, winding of signal 7, back contact 34 of relay 6S, wire 35, front contact 36 of relay 4TR, and front contact 37 of relay 5YGP. The mechanism of signal 5 is energized with positive polarity by a circuit including front contact 38 of relay 3YGP, common line wire 24, winding of signal 5, back contact 39 of relay 4S, line wire 40, front contact 41 of relay 2TR, and front contact 42 of relay 3YGP. The energization of signal 5 with positive polarity causes the contacts of signal 5 to be actuated to their right-hand positions to close a circuit for the energization of relay 5YGP through contact 43 of signal 5 in its right-hand position and through back contact 44 of relay 5S connected in multiple with front contact 45 of relay 4TR.

Upon entrance of a train into the block, or upon setting up a route into the block by centralized traffic control, the conventional tumble-down takes place to put all opposing signals to stop. Thus, for example, putting signal 3 to stop by opening its line circuit causes the dropping away of relay 3YGP by opening the circuit for this relay at a contact comparable to contact 43 of signal 5. The dropping away of relay 3YGP removes energy from the line circuit for the energization of the mechanism of signal 5 at front contact 38. The back contact 42 of relay 3YGP connects energy of the opposite polarity to the common wire 24, but the closure of front contact 46 of the stick relay 3S is required in order that the mechanism of signal 5 may become energized with the opposite polarity. Thus in a similar manner the signal 7 is put to stop because of the repeater relay 5YGP being dropped away upon the opening of its circuit at contact 43 of the mechanism of signal 5. The dropping away of relay 5YGP opens the circuit at front contact 33 which is normally effective for the energization of the line circuit governing signal 7, the back contact 33 being ineffective to apply the opposite polarity of energization to the line circuit because of the front contact 47 of relay 5S being opened. As this tumble-down becomes effective, the dropping away of the relays YGP for the westbound signals at the respective double immediate signal locations is effective to energize the lamps of the respective eastbound signal mechanisms such, for example, as the closure of back contact 48 is effective to energize the lamp of signal 2.

To consider the mode of operation upon passage of a train it will be assumed that an eastbound train enters the block, setting the opposing signals 3, 5, and 7 at stop, and approaches signal 2. The entrance of the train into the track section 2T puts signal 2 to stop by opening the signal control circuit at front contact 22, and before the signal repeater relay 2YGP (not shown) has time to drop away, a stick relay 2S (not shown) is picked up in a manner comparable to that which will be described with respect to the picking up of the stick relay 4S for signal 4.

When the train enters the track section 4T, the dropping away of the track relay 4TR opens the circuit for the mechanism of signal 4 at front contact 28, and before the signal repeater relay 4YGP has time to be dropped away, the stick relay 4S is picked up by the energization of a circuit including back contact 49 of relay 4TR, front contact 50 of relay 4WGP, back contact 51 of relay 5S, and back contact 52 of relay 5YGP. This circuit is only momentarily energized through front contact 50 of relay 4YGP because relay 4YGP becomes dropped away in response to the signal 4 being put to stop, but the relay

4S is maintained energized by a stick circuit during the dropping away of relay 4YGP extending through back contact 49 of relay 4TR, front contact 53 of relay 4S, back contact 51 of relay 5S, and back contact 52 of relay 5YGP. Energy is also applied to this stick circuit through back contact 50 of relay 4YGP when that relay becomes dropped away. Thus the stick relay 4S is maintained picked up until the signal 4 is again energized so as to cause the relay 4YGP to be picked up.

In accordance with the picking up of the stick relay 4S, energy of reverse polarity is applied to the signal 2 (after track section 2T has become unoccupied in the rear of the train) through back contact 23 of relay 3S, front contact 22 of relay 2TR, line wire 21, front contact 54 of relay 4S, and back contact 25 of relay 4YGP. Thus the mechanism of signal 2 is actuated to a position for the display of a yellow aspect in case there is a following train approaching signal 2 so as to cause the relay 3YGP to be dropped away to energize the lamp of signal 2 by the closure of back contact 48.

Upon further progress of the eastbound train so as to accept the signal 6, the stick relay 6S is picked up by the energization of circuit means comparable to that which has been described for the relay 4S. Relay 6S when picked up energizes the mechanism of signal 4 (when track section 4T becomes unoccupied) with reverse polarity through front contact 55 of relay 6S and a circuit comparable to the circuit that has been described for the energization of signal 2 with reverse polarity. Signal 4 when thus energized actuates the contacts 32 and 56 to their left-hand positions and thus provides for the picking up of relay 4YGP. The picking up of relay 4YGP pole changes the line circuit for the energization of signal 2, and thus causes the operation of the mechanism of signal 2 to its clear position. The picking up of relay 4YGP opens the stick circuit for relay 4S at back contact 50.

The mode of operation upon passage of westbound trains is different from that which has been described relative to the passage of eastbound trains in that the picking up of the stick relay is effected when the train enters the track section in approach of the associated signal. Thus, as a westbound train approaches signal 5, the entrance of the track section 4T causes the picking up of the stick relay 5S by the energization of a circuit including back contact 57 of relay 4TR, front contact 58 of relay 5YGP, back contact 59 of relay 4S, and back contact 60 of relay 4YGP. The closure of front contact 61 of relay 5S shunts front contact 58 of relay 5YGP out of the circuit just described, and stick energy is maintained on the relay 5S after the track section 4T becomes unoccupied in the rear of the train through back contact 58 of relay 5YGP.

In a similar manner, the entrance of the track section 2T by a westbound train causes the picking up of the stick relay 3S which is associated with signal 3 by the closure of back contact 62 of relay 2TR, the circuit for the control of relay 3S being comparable to the circuit that has been specifically described for the relay 5S.

In accordance with the relay 5S being picked up, when the track section 4T becomes unoccupied in the rear of the westbound train, the mechanism of signal 7 becomes energized with reverse polarity over the line circuit through front contact 47 of relay 5S so as to condition the mechanism of signal 7 for a caution indication for a following train. The picking up of the signal repeater relay (not shown) for the signal 7 reverses the polarity of energization of the next track section in the rear to provide a clear control for the next signal in the rear.

As the westbound train progresses further so as to cause the track section 2T to become unoccupied in the rear of the train, the signal 5 becomes energized over the line circuit with reverse polarity through front contact 46 of relay 3S, and its energization causes the picking up of relay 5YGP through contacts 43 and 63 of the

mechanism of signal 5 in its left-hand position and front contact 45 of relay 4TR. With this relay picked up, the stick relay 5S is dropped away because of its circuit being opened at back contact 58 of relay 5YGP and at back contact 57 of relay 4TR. The dropping away of relay 5YGP applies normal polarity to the line circuit for the control of signal 7 by the energization of a circuit which has been described.

As the westbound train progresses further so that signal 3 becomes energized with reverse polarity, the relay 3YGP is picked up upon the closure of front contact 64 of relay 2TR, and the picking up of this relay causes the dropping away of the stick relay 3S and applies normal polarity to the line circuit for the control of signal 5 to operate the mechanism of that signal to its clear position.

Having thus described the apparatus involved at specific intermediate signal locations as one embodiment of the present invention, it is to be understood that the principles of the invention can be applied to other track layouts and systems using other types of signals and modified forms of signal control and track circuits, and that various modifications, adaptations, and alterations may be applied to the specific form of the invention herein disclosed according to the requirements of practice except as limited by the appended claims.

What I claim is:

1. In an absolute permissive block signalling system, apparatus at a double intermediate signal location comprising in combination, signals at said location for governing traffic in both directions, a track circuit adjoining said location having a track relay, a signal repeater relay for each of the signals, circuit means for energizing said signal repeater relay when its associated signal is clear and for deenergizing said signal repeater relay when the associated signal is put to stop, a directional stick relay for each of the signals, pickup circuit means for energizing each of said directional stick relays through a back contact of said track relay and through a front contact of said signal repeater relay for the associated signal, whereby the stick relay for one signal is picked up when a train accepts the signal and the stick relay for the signal for the opposite direction of traffic is picked up when a train is on the track circuit in approach to the signal.

2. In an absolute permissive block signalling system, apparatus at a double intermediate signal location comprising in combination, a track circuit adjoining said location, said track circuit having a track relay, a signal at said location for governing traffic in each direction, a slow acting signal clear repeater relay for each signal, directional stick relays for the respective signals for governing the energization of line wires extending to signals in the rear, circuit means for energizing said signal repeater relay in accordance with the associated signal being clear, said circuit means being effective to deenergize said signal repeater relay when the associated signal is put to stop, a directional stick relay for each of the signals pickup circuit means for energizing each of said stick relays in response to the dropping away of said track relay provided that said signal repeater relay for the associated signal is picked up, stick circuit means for

maintaining each of said stick relays energized for a time subsequent to the dropping away of said signal repeater relay for the associated signal, and line circuit control means energized in response to the energization of said stick relay for governing the next signal in the rear.

3. In an absolute permissive block signalling system, apparatus at a double intermediate signal location comprising in combination, signals at said location for governing both directions of traffic, a track circuit adjoining said location for the approach to one of said signals, a track relay responsible to energization of said track circuit, a slow acting signal clear repeater relay for each signal, directional stick relays for the respective signals for governing the energization of circuits for the control of the respective signals in the rear, circuit means for energizing said signal repeater relay in accordance with the associated signal being cleared, said circuit means being effective to deenergize said signal repeater relay when the associated signal is put to stop, pickup circuit means for energizing each of said stick relays in response to the dropping away of said track relay provided that said signal repeater relay for the associated signal is energized and provided that said stick relay for the opposing signal is dropped away, stick circuit means for maintaining each of said stick relays energized for a time subsequent to the dropping away of said track relay for the associated signal, and line circuit means energized in response to the energization of said stick relay for governing the next signal in the rear.
- 20 4. In an absolute permissive block signalling system, apparatus at a double intermediate signal location comprising in combination, a signal at said location for each direction of traffic, a track circuit adjoining said location in approach to a given one of said signals, said track circuit including a track relay, a slow acting signal clear repeater relay for each signal, directional stick relays for the respective signals for governing the energization of line circuits extending to respective signals in the rear, circuit means for energizing said signal repeater relay when the associated signal is clear and for deenergizing said signal repeater relay when the associated signal is put to stop, pickup circuit means for energizing each of said stick relays in response to the dropping away of said track relay provided that said signal repeater relay for the associated signal is picked up, said pickup circuit means including back contacts of the stick and signal repeater relays for the opposing signal, stick circuit means for maintaining each of said stick relays energized for a time after said track relay is picked up, and line circuit means associated with each signal and extending to the next signal in the rear having its energization governed by said stick relay for the associated signal.
